SPARK PLUG

Douglas W. Gregory, Vergennes, Vt., and Egidio R. Baldassare, New York, N. Y., assignors to Simmonds Aerocessories, Inc., Tarrytown, N. Y., a corporation of New York

Application September 22, 1948, Serial No. 50,582

5 Claims. (Cl. 123—169)

1

This invention relates to improvements in a method of making spark plugs and in the spark plug made thereby. In a more particular sense the invention relates to a method of bonding metals with ceramics, for example a metal electrode to an insulator to form a gastight seal between the two.

Various methods have been employed for the sealing of electrodes in spark plug or igniter insulators. One successful method comprises a seal formed by melting glass containing graphite or metal powder inside the ceramic insulator and the ceramic and the metallic electrode contained therein in accordance with U. S. Patent 2,106,578. In contradistinction, processes have been developed for the forming of spark plug center electrodes by means of casting metal in the insulator bore to make permanent and fixing engagement with a sparking tip located in the insulator bore at its sparking end in accordance with U. S. Patent 2,162,062, the advantage thus gained being the formation of an electrical conductor having form, position and properties which make for the increased conduction of heat from said sparking tip and, less certainly, from the insulator nose, while mechanically fixing and at the same time integrally uniting the parts in the insulator.

Spark plugs made using this latter process as well as those produced according to the designs and processes set forth in British Patents 533,759, 547,119, 559,805 and 562,064 have been found to show gas leakage as in the usual method of pressure testing spark plugs. For such reason it has been necessary to use additional sealing means such as represented by the above cited U. S. Patent 2,106,578 in addition to the subject casting process in order to insure gas-tightness considered essential to consistent performance in spark plug operation.

Plugs made by casting or hot forming silver in the insulator have been examined in detail by breaking the insulator and exposing the cast metal core conductor. It was found that the cast metal core was smooth and that it did not adhere to the wall of the insulator. The insulator had apparently served merely as a mold for casting or forming the silver.

According to the present invention a method has been discovered by which a cast metal is bonded directly to a ceramic material in such a manner as to withstand rupture of the metal or ceramic in areas contiguous to the bond without failure of such bond. Particularly, the method relates to bonding a cast metal conductor directly to the wall of an insulator to provide a seal

against the passage of gas through the insulator bore and to enhance the interchange of heat between the metal and ceramic insulator components.

5 The primary object of the invention is, therefore, to provide an improved method for bonding a metal conductor to the inside wall of a spark plug insulator.

Another object of the invention is to provide a method of sealing a spark plug insulator with respect to its electrode in such a manner as to prevent gas leakage.

Another object of the invention is to provide an improved method of bonding a metal to a ceramic material.

Another object of the invention is to provide an improved spark plug in which the electrode conductor is bonded to the inside wall of the spark plug insulator.

20 According to a preferred form of the invention the improved spark plug is manufactured by the steps of mounting a metal sealing cone or spike in the lower portion of a spark plug insulator, the cone being electrically connected to a sparking tip extending from the tip of the insulator providing a body of molten metal having a melting point of approximately that of silver around the cone and to a considerable depth in the insulator, inserting a second metal sealing cone or spike pointed downwardly in the insulator above the body of molten metal, and applying pressure to the second cone to drive it into and to apply pressure to the molten metal in the insulator, whereby the molten metal is driven suddenly into intimate contact with the hot inside wall of the insulator and bonded thereto.

25 In a specific form of the invention the sealing cone used in the bottom of the insulator is preferably of nickel, while the second cone is preferably of steel and nickel and silver plated, with the silver subsequently brazed as in hydrogen.

30 The improved method of the present invention includes other details and features which are referred to hereinafter in the following description of the invention taken in connection with the drawings which form a part of this application.

35 In the drawings:

Fig. 1 is a vertical or longitudinal view of a spark plug insulator of conventional construction showing the relationship of the parts in the initial stage of the process.

40 Fig. 2 is a view similar to that of Fig. 1, showing the relationship of the parts after the silver or other metal has been melted in the insulator.

Fig. 3 is a longitudinal sectional view showing the relationship of the parts at the conclusion of the process.

Figs. 4, 5, 6 and 7 show modified forms of upper sealing cones or spikes which may be used in carrying out the improved process;

Figs. 8 and 9 show modified forms of lower sealing cones or spikes.

Referring to Figs. 1 to 3 inclusive, of the drawings, the improved spark plug of the present invention is made by providing a spark plug insulator 10 of conventional design and made, for example, by sintering aluminum oxide or other suitable ceramic. This insulator, preferably of an aluminum oxide type, has an upper relatively long bore 12 of large diameter, a lower relatively long bore 14 of substantially smaller diameter, and a tip bore 16 substantially smaller than the bore 14 and preferably of the correct size to fit a sparking tip such as the metal tip 18, or an extension of a cone 20, to which a relatively shorter sparking tip may be appended. The first step in the process is to provide a lower sealing cone or spike such as the spike 20 which is preferably of nickel, and which is also large enough or may be mechanically up-set or otherwise processed to preclude its complete passage outwardly through bore 16. The lower sealing cone or spike 20 may be provided with an extension of suitably small diameter to project through bore 16 whereafter it may attach to the sparking tip 18 of relatively short length. In the form shown in Fig. 1, lower cone 20 is welded to the sparking tip 18, the welding joint being shown at 22, and as providing a rim resting in the lower portion of the bore 14. It is not necessary that the cone or spike 20 be of larger diameter than that of the sparking tip 18, but it preferably extends substantially into the bore 14. After the cone 20 is in place a section of a silver wire 24 is set in the insulator on the cone so that when it melts it will somewhat more than fill the bore 14. Instead of using silver wire powdered silver or other form of silver or a silver alloy may be used. Copper may also be used.

The insulator 10 with the elements shown in Fig. 1 is set in upright position in a suitable furnace in which the insulator is heated to a temperature above 1760° F., which is sufficient to melt the silver and cause it to run down in the bore 14 and surround the cone 20 in the manner shown in Fig. 2 of the drawings. If the cone 20 is welded or otherwise attached to the sparking tip 18 prior to starting the process, the arrangement is preferably such that none of the silver comes in contact with the tip 18 which is preferably of platinum or a platinum alloy of tungsten. The insulator containing the molten silver is removed from the furnace to a specially arranged press, after which an upper sealing cone or spike member 26 is quickly inserted into the insulator and plunged or driven into the molten metal by applying a tool under pressure to the upper part of the cone. The cone 26, as shown in Fig. 2, includes a pointed spike section 28 and an upper open top shell section 30 into which the tool for applying the pressure may be inserted. The entire cone 26 may be of Bessemer steel such, for example, as screw stock and silver plated.

The pressure applied to the cone 26 should be somewhat of the order of 4,000 pounds per square inch and applied quickly but over a period of a few seconds rather than instantly. When the cone 26 is plunged into the body of molten silver shown at 32 in Fig. 2, the relatively cold metal

cone quickly chills the silver and at the same time forces the melted silver against the hot wall of the insulator 10. The shape of the cone 26 furthermore causes the chilling of the silver from the inside out. When the silver 32 has frozen it forms an intimate contact with the lower cone 20, with the upper cone 26 and with the contiguous insulator wall, especially in the areas adjacent to members 20 and 26.

Fig. 3 shows a vertical section through the insulator after the foregoing operations have been completed and it will be noted that the silver 32 is thoroughly bonded to the inside wall of the insulator 10 and that the lower cone 20 extends into the body of silver while the sparking tip 18 has not been contacted by the molten silver in the casting operation. The upper part of the body of silver 32 completely surrounds the lower portion of the cone 26, the tip of which is somewhat deformed to provide a sort of lock or enlarged portion around and over which the cast silver extends. The cone 26 is therefore completely anchored in the body of silver. It appears that when the spike 28 is quickly forced into the molten body of silver the temperature is sufficient to soften the metal causing it to deform under the pressure applied, into a form similar to that shown in Fig. 3.

The upper cup-shaped or hollow section 30 of the cone 26 is one convenient form of cone from the standpoint of applying pressure in the operation and also from the standpoint of using the cup to receive a resistor or a terminal connector such as might be required in spark plug design.

The invention is not restricted to the use of a particular form of upper sealing cone shown in Fig. 2 of the drawings, but one of the forms shown in Figs. 4 to 7 inclusive, may be used. In Fig. 4 the cone 34 includes the upper hollow section 30 similar to that of cone 26 and an anchor section 36 which is adapted to be driven into the molten metal in the insulator so that the metal will solidify above the section 36 and anchor the cone therein. The form shown in Fig. 5 is somewhat similar to that shown in Fig. 4, but is provided with a button type anchor member 38 which is adapted to be embedded into the molten silver under pressure, and which transmits a greater portion of the driving force downwardly through the silver column beneath it.

The cone structure shown in Fig. 6 includes a body 40 provided with the upper cup-shaped section and with a low melting point anchor member 42 keyed to the body 40 but provided with an end section adapted to be embedded in the molten silver and to be melted thereby. The melting of the end section of the member 42 provides an intimate fused bond for anchoring the cone in the silver body.

The sealing cone shown in Fig. 7 includes a pointed spike section 43 similar to the spike 28 of the cone 26, an intermediate enlarged section 44 of slightly larger diameter than the bore 12 of the insulator. This sealing cone also includes an upper pointed section 45 of about the same diameter as the spike section 43. The sealing cone shown in Fig. 7 is driven into the body of molten silver in a manner similar to that of the sealing cone 26, the driving member extending around the upper section 45 and bearing on the shoulder of the section 44. The entire sealing cone is of solid metal and functions in much the same manner as the sealing cone or spike member 26. After the sealing cone is driven into the molten silver and the spark plug assembled, the

upper section 45 serves to engage the conductor or damping material in the bore 12 in accordance with the usual practice. The cones shown in Figs. 4 to 7 are advantageously made of Bessemer steel screw stock and silver plated.

Fig. 8 of the drawings illustrates a modified form of lower sealing cone construction comprising a pointed upper portion 46 of somewhat larger diameter than the bore 16, the section 46 being beveled down to a smaller cylindrical section 48 adapted to fit the bore 16 and extend therethrough. The lower end of the cylindrical section 48 is welded or brazed to a sparking tip 50 which is preferably of platinum or an alloy as referred to. This tip may be conveniently welded to the section 48 after the upper cone is installed. The insulator 10 shown in Fig. 8 may have a countersunk portion 52 at the lower end of the bore 16 so that the weld between the tip 50 and the section 48 is up within this countersunk portion, as indicated. The section 48 will therefore be somewhat shielded from high temperatures and spark conditions existing in the cylinder of the internal combustion engine in which the spark plug is used.

Fig. 9 shows a modified form of lower sealing cone or spike made of the same materials as that shown in Fig. 1, and comprising a sparking tip 54 welded to a spike or cone 56 by an extending rim-like welding joint 58 having the same function as the welding joint 22 in Fig. 1. The spike 56 is of somewhat larger diameter than the tip 54 and is provided with a plurality of superposed annular grooves 60 of the shape shown. One or more grooves 60 may be used, which are adapted to receive molten silver when the pressure is applied, as described above. The sealing cone shown in Fig. 9 therefore provides a structure, after casting of the silver, in which one or more annular flanges of silver in the groove or grooves 60 positively retain the spike or cone in the silver casting and aid in forming a tight immovable connection adapted to facilitate heat flow from the sparking tip.

Spark plugs made by the process of the present invention have been used and tested and it has been found that the body of silver 32 is very thoroughly bonded and sealed to the side wall of the insulator 10. Many spark plug units made in accordance with the above procedure have been cut in two lengthwise to determine what happens to the upper cone 26. A typical result is shown in Fig. 3. Furthermore, spark plug units made in accordance with the process of the present invention have also been broken up around the silver-casting to investigate the bond between the body of silver and the wall of the insulator 10.

In breaking up the lower portion of the insulator it was found that it had to be broken into relatively small pieces in order to remove most of it from the body of silver 32. Even then, in a large majority of cases, the body of silver was substantially completely covered with the material of the insulator in chips and layers, showing that the bond between the silver and the insulator was stronger than the internal bond of the insulator. In many cases where attempts were made to break the insulator away from the body of cast silver it was found that a considerable number of pieces of the insulator would adhere tenaciously to the body of silver and that further breaking of these pieces would still leave an irregular coating of the insulator material on the silver all along the casting.

Not all, but a large majority of the insulators, 75

broken up to determine the adherence of the silver to the insulator, show a uniform bond between the silver and the ceramic insulator. However, in all cases there was definite bonding between the silver and the insulator, and all units were leak-proof, as distinguished from spark plug units made by previously known processes, such as those referred to above. Spark plugs made by previously known silver casting methods were broken and examined to find only that the outside of the silver cast was smooth and not bonded to the insulator.

The phenomenon involved in the bonding of the silver to the ceramic insulator without the use of any bonding agent is not fully understood, but, important as are the pressure relationships of the process, investigation has shown that nickel, such as the nickel cone 20 or 56, facilitates bonding. There may be some complicated physical, chemical or catalytic action involved, or two or more such actions, but that has not been determined. It does appear from investigation, however, that the carrying out of the process in an atmosphere of hydrogen adversely affects the bonding.

It also appears not altogether desirable to make cone 20 of a material which will readily form a fusion bond with the silver or of heat conducting metal. This is possibly one of the keys to the success of the process for reasons which may be explained as follows: In an insulator which is cooling after processing as described, the bond between the ceramic and the silver is greater than that between the silver and the nickel of cone 20. Stresses set up in this region as a result of the differences between the contraction rates of the silver and ceramic are thus relieved at the silver-nickel interface where break-down may occur without opening up any leakage paths. In order to off-set possible maladjustment of the heatflow pattern as affecting heat picked up by the sparking tip, cone 20 may be made to contain grooves as shown in Fig. 9, such that will insure intimate mechanical pressure exerted between such grooves during the contraction phase of the process. Heat flow at the cone to silver interface may also be insured by the employment of plated or brazed coatings which cover only a portion of the sealing cone or welded extensions of a metal or metals which enter into fusion bonding with the molten silver.

The unusual results obtained with spark plug units may in some respects be due to the positions and manner of using the spaced upper and lower cones, or to these factors in combination with the use of nickel and presence of air. When the upper cone is plunged into the molten silver under pressure, the upper and lower cone tips appear to act as plungers and force the molten silver toward the hot wall of the insulator 10. At the same time the cooling is most rapid at the top and bottom and from the inside of the body in view of the cold upper cone and the conduction of heat from the cone 20 to the tip 18. However, this may not entirely explain the bonding phenomenon or results because it has been found that in a great majority of cases the entire length of the silver body was intimately bonded to the inside wall of the insulator, whereas the tips of the cones are spaced substantially apart as shown in Fig. 3.

The invention has been described above in connection with a specific illustration thereof, but it is to be understood that certain variations and other uses are possible. The use of silver as

a sealing or bonding material has been found to give certain advantages over other metals because it can be heated and processed in the open atmosphere without a special type of furnace to prevent oxidation. Other metals or alloys melting in the neighborhood of the melting point of silver may be used, for example, copper or a metal powder mixture consisting of 80% silver, 9% iron, 9% nickel, 1% carbon and 1% flux such as borax. Other silver alloys may be used, as for example, sterling silver or an alloy containing from 1% to 5% of nickel.

According to the preferred form of the invention, the lower sealing cone is made of pure nickel or steel plated with nickel, while the upper sealing cone is of steel plated successively with nickel and then with silver, the latter of which is subsequently hydrogen brazed to the nickel undercoating. In some cases a copper undercoating may be used in place of nickel.

The process may be employed for the bonding of metals to ceramic materials and to glass for various purposes. Many insulating materials are glass or contain glass.

What is claimed as new is:

1. A spark plug including a central insulator having a sparking tip of corrosion-resisting metal projecting from its lower end, a metal sealing member comprised of nickel connected to said tip and extending into said insulator, a body of cast metal containing silver surrounding said member and intimately bonded to the inside wall of the insulator by direct contact of the cast metal with the insulator wall, and an upper sealing member anchored in said cast metal body by means of a projection extending into the body and partially enclosed thereby, the upper portion of the upper sealing member substantially fitting the bore of the insulator.

2. A spark plug insulator construction comprising a ceramic body having a longitudinal bore and a tip portion from which a metal sparking tip of corrosion-resisting metal extends, a cast metal body in the insulator bore in the portion adjacent said sparking tip, a nickel spike electrically connected to said tip and embedded in said metal body, and a second metal member having an elongated pressure-exerting and pointed anchoring portion extending into the opposite end of said metal body and anchored therein, the cast metal body and the wall of the insulator being bonded together by a bond adapted to join and seal the metal body with respect to the insulator.

3. A spark plug insulator construction comprising an elongated ceramic insulator having a longitudinal bore, a nickel connector and sealing member located at its operating end and extending into the insulator bore as well as extending outwardly from the operating end of the insulator, a metal sparking tip of corrosion and erosion resisting metal secured to the outwardly-extending end of said member, and a cast metal body in the bore in contact with and sur-

rounding said nickel connector said cast metal body being bonded directly to the inside wall of the insulator bore with a strong intimate bond adapted to provide an effective seal against the leakage of gas between the metal body and the insulator.

4. A spark plug including a central ceramic insulator having an axial bore, a sparking tip of corrosion resisting metal projecting from the lower end of the insulator, a metal sealing member connected to said tip and extending into the bore of said insulator, a body of cast metal containing silver surrounding said member and intimately bonded to the inside wall of the insulator by direct contact of the cast metal with the insulator wall, and an upper metal sealing member plated successively with nickel and silver, said upper sealing member being anchored in said cast metal body by means of a projection extending into the body and partially enclosed thereby, the upper portion of said upper sealing member substantially fitting the bore of the insulator.

5. A spark plug insulator construction comprising an elongated ceramic insulator having a longitudinal bore, a metal sealing-member extending from the bore at the operating end of the insulator and also extending into the bore and terminating therein with a pointed end as a sealing means, a cast metal body in the insulator bore surrounding and bonded to the portion of the metal sealing member in the bore, said cast metal body extending in the bore beyond said pointed end, and a metal member having an elongated pressure-exerting pointed anchoring portion extending into the cast metal body at its end remote from the operating end of the insulator and anchored in and bonded to the cast metal body in spaced relation to said pointed end, said cast metal body being bonded directly to the inside wall of the insulator bore with a strong intimate bond adapted to provide an effective seal against the leakage of gases between the cast metal body and the insulator.
